(57) **CLAIM**

The ornamental design for a re-closable lid, as shown and described.

DESCRIPTION

FIG. 1 is a top plan view of a re-closable lid with the insert structure shown in a first condition of use.

FIG. 2 is a top perspective view of the re-closable lid in the first condition of use.

FIG. 3 is a bottom plan view of the re-closable lid in the first condition of use.

FIG. 4 is a top plan view of the re-closable lid with the insert structure shown in a second condition of use.

FIG. 5 is a top perspective view of the re-closable lid in the second condition of use.

FIG. 6 is a bottom plan view of the re-closable lid in the second condition of use.

FIG. 7 is a top plan view of the re-closable lid with the insert structure shown in a third condition of use.

FIG. 8 is a top perspective view of the re-closable lid in the third condition of use.

FIG. 9 is a bottom plan view of the re-closable lid in the third condition of use.

FIG. 10 is a first edge view of an insert structure removed from the re-closable lid.

FIG. 11 is a top plan view of the insert structure removed from the re-closable lid.

FIG. 12 is a second edge view of the insert structure removed from the re-closable lid.

FIG. 13 is a bottom plan view of the insert structure removed from the re-closable lid.

FIG. 14 is a third edge view of the insert structure removed from the re-closable lid.

FIG. 15 is a fourth edge view of the insert structure removed from the re-closable lid.

FIG. 16 is a top plan view of a lower body of the re-closable lid with the insert structure removed therefrom.

FIG. 17 is a top perspective view of the lower body of the re-closable lid with the insert structure removed therefrom.

(Continued)

FIG. 18 is a first edge view of the re-closable lid.
 FIG. 19 is a second edge view of the re-closable lid.
 FIG. 20 is a third edge view of the re-closable lid.
 FIG. 21 is a fourth edge view of the re-closable lid; and,
 FIG. 22 is a top perspective view of the re-closable lid in an
 environment a fourth condition of use.
 The broken lines in FIGS. 1-14, 16-18, and 20-22 illustrating
 text, arrows, circular features, arcuate features, and an
 oblong insert feature form no part of the claimed design. The
 broken lines in FIG. 22 illustrating a cup and a straw depict
 environmental subject matter that forms no part of the
 claimed design.
